UNITED STATES PATENT OFFICE.

WILLIAM R. LIVERMORE AND ANDREW H. RUSSELL, OF THE UNITED STATES ARMY.

CARTRIDGE-PACKING CASE.

SPECIFICATION forming part of Letters Patent No. 278,980, dated June 5, 1883.

Application filed August 21, 1882. (No model.)

To all whom it may concern:

Be it known that we, WILLIAM R. LIVERMORE and ANDREW H. RUSSELL, both of the United States Army, jointly have invented an 5 Improved Cartridge Case or Holder, of which the following is a specification.

Our cases are designed for carrying cartridges for magazine-guns, and are so constructed that they serve as means for feeding 10 the cartridges to the guns. The cases can be made of any suitable size for any required number of cartridges, and are to be carried in the belt or upon the person of the soldier. The 15 class of guns with which they may be used is well known, and is illustrated in our Patent No. 221,079, granted October 28, 1879.

We are aware that cartridge cases designed 20 for such purposes are old; but our improved cases are different in construction and operation from any heretofore made.

In the accompanying drawings, Figure 1 is a perspective view of a cartridge-case filled 25 with cartridges. Fig. 2 is a section on the line 2 2 of Fig. 1, and Fig. 3 a section on the line 3 3 of Fig. 2.

The case A may be made of light sheet metal, card-board, or other suitable material, and is preferably formed in a single piece. The blank from which it is made may be stamped or cut 30 out of the requisite contour, so that when folded it will present the shape illustrated in the drawings—that is, the top of the box is formed of two wings, B B, which are folded down to meet the side flaps, C C'. A continuous slot 35 or opening, d, is left up the side and across the top of the case. The bottom is open, and the cartridges are preferably inserted at that end and retained therein by a check-tongue, E, which may be a direct continuation of the solid 40 side of the box, or may be an independent piece secured thereto. The case should of course be made of the most appropriate shape to hold the cartridges, and as the shell end of the cartridge is larger than the projectile end one 45 side of the box is preferably made correspondingly larger than the other.

Upon reference to Fig. 3, which shows the shape of the case in horizontal cross-section, as we prefer to make it, it will be seen that

the back of the case e is crimped or bent in, 50 and that the flap C is correspondingly inclined inwardly, so that the cartridges are pinched or clamped between them, and are thus held in place under slight tension. While we prefer to make the boxes of this shape, we do not 55 limit ourselves, so far as the primary feature of our invention is concerned, to this or any particular cross-section of box.

The check-tongue E may be either a spring-tongue, so far as some features of our invention 60 are concerned, a bent non-resilient tongue, or a retainer of any kind, the sole requisite being that it shall have sufficient strength or tension to normally hold the cartridges in place in the case for transportation and general handling, 65 but when a gun is being loaded will yield to pressure upon the cartridges and permit them to pass into the receptacle of the gun. In loading a gun the thumb or finger may be placed upon the top cartridge and a sufficient 70 pressure exerted to force the cartridges past the tongue into the magazine.

By forming our improved case with a slot 75 extending entirely up the side and across the cover of the box, the thumb may be placed on the upper cartridge and carried down entirely through the side slot, thus positively forcing all of the cartridges from the case. Of course any kind of a retainer in the bottom of the box to be removed or operated in any way 80 may be used in connection with a case thus formed.

The primary features of our invention consist, first, in a cartridge-case having a continuous slot which extends up the side and 85 across the top, for the purpose set forth; and, second, in such a case a check or tongue at the bottom which ordinarily retains the cartridges in place, but will yield to a direct pressure upon the cartridges in loading. We therefore do not limit ourselves to the above-described or any special method of making the cases.

For transportation these cases may be covered with paper or cloth pasted or otherwise 95 fastened to them, the coverings being preferably removed when the cases are placed in the belt of the soldier for use.

While our cases are more especially designed for use with magazine-rifles, they may of course be used for machine-guns and like large ordnance.

- 5 We are aware that heretofore match-boxes have been made with entirely open tops for the insertion of matches, slotted slides, and bottoms closed by elastic tongues, and we therefore make no claim to such subject-matter.
- 10 We are also aware that magazines and cartridge-feeders for guns have heretofore been made with slotted sides and open tops, and we therefore make no claim to such an organization, but limit ourselves to the subject-matter set forth in the following claims.

15 Having thus described our invention, what we claim as new is—

- 20 1. The improved cartridge transporting or packing case herein described, formed with a continuous open slot which extends up the side and across the cover of the case, which prevents the escape of the cartridges, and a retainer at the bottom or entrance for holding the cartridges in place in the case.
- 25 2. A cartridge transporting or packing case for feeding magazine-guns, which incloses the cartridges and has its bottom closed by a non-resilient yielding tongue, which is curved to partly embrace the lower cartridge trans-
- 30 versely to its length, and which ordinarily holds the cartridges in place in the case, but will yield without recoil to a direct pressure upon the upper cartridge and permit them to pass into the gun.
- 35 3. The combination, substantially as set forth, of a cartridge-case having a continuous slot extending up the side and across the cover

thereof, with a tongue or check which ordinarily holds the cartridges in place in the case, but will yield when pressure is applied to the 40 cartridges and permit them to pass out of the case.

4. The herein-described cartridge-case, formed from a single piece of metal, with the retainer E, top wings, B B, and side flaps, C C', folded, as shown, to receive the cartridges and leave a continuous slot up one side and across the cover.

5. A cartridge transporting and feeding case for magazine-guns, contracted transversely at 50 or about its middle in line with its length, so as to pinch or clamp the cartridges transversely and hold them under tension, as described.

6. The combination, substantially as herein 55 set forth, of a cartridge-case formed with a continuous slot extending up its side and across its top, and having its back crimped or bent in and its front flap inclined inwardly, so that the cartridge is clamped between the flap and back, and a tongue or check which ordinarily holds the cartridges in place in the case, but permits them to pass from the case when pressure is applied to them.

In testimony whereof we have hereunto subscribed our names.

WM. R. LIVERMORE
ANDREW H. RUSSELL.
